UNITED STATES PATENT OFFICE.

ROBERT O. BOARDMAN, OF GRAND RAPIDS, MICHIGAN, ASSIGNOR TO MERGENTHALER LINOTYPE COMPANY, A CORPORATION OF NEW YORK.

LINE-CASTING MACHINE.

1,081,806.

Specification of Letters Patent. Patented Dec. 16, 1913.

Application filed November 21, 1911. Serial No. 661,513.

To all whom it may concern:

Be it known that I, ROBERT O. BOARDMAN, of Grand Rapids, county of Kent, and State of Michigan, have invented a new and useful Improvement in Line-Casting Machines, of which the following is a specification.

My invention relates to line casting machines of the Mergenthaler class and similar machines, in which circulating matrices representing the individual characters are stored in a channeled magazine and released therefrom by escapement devices controlled by finger keys or otherwise.

The invention is applicable more especially to machines in which several superimposed magazines are employed, each containing a font or series of matrices, but may be employed in machines having single magazines.

The invention consists in an escapement device movable laterally in relation to the matrices, and in coöperating matrices longitudinally grooved or recessed for a portion of their length, so that after an escapement has been moved laterally to release a matrix it may be returned into the groove in the side of the outgoing matrix, to a position in which it will be certain to engage and arrest a succeeding matrix.

Referring to the drawings, Figure 1 is a vertical cross section through the forward end of a series of magazines and my escapement mechanism adjacent thereto, together with the adjacent parts. Fig. 2 is a perspective view illustrating one of the escapements and the matrix, showing the manner in which the escapement holds the matrix in its normal position. Fig. 3 is a similar view showing the manner in which the escapement enters the channel or recess in the outgoing matrix. Fig. 4 is a front elevation of a series of escapements and their actuating devices.

Referring to the drawings: A, A' etc. represent a series of inclined magazines consisting of parallel longitudinally grooved plates, adapted to receive and guide the edges of the matrices B, as usual in Mergenthaler machines, and familiar to those skilled in the art.

C represents a vertically movable plate or frame, the rear face of which lies immediately in front of the magazines, to prevent the escapement of matrices from those magazines which are not for the moment

in action. This plate is provided with a horizontal slot or opening, which may be brought opposite any one of the magazines to permit the escape of the matrices therefrom, as shown in Fig. 1.

D represents the matrix controlling escapement, which consists of a vertical elastic arm mounted at its upper end so as to bend laterally, and having at the lower end a lateral lip d, which overlaps the forward end of the foremost matrix in order to prevent its escape from the magazine. The release of a matrix is effected by moving the escapement laterally, as shown in dotted lines in Fig. 4, until it disengages from the matrix.

In order that the second matrix may be arrested with certainty, and prevented from escaping, each matrix is provided with a longitudinal recess or channel b, as shown in Figs. 1 and 3, this recess extending from the upper or rear end of the matrix to a point near the forward end, which is preferably left of full thickness. When the matrix is thus constructed the escapement may be permitted to return to its normal position very quickly, and while the matrix is passing it, for the reason that the lip will in such case enter the recess b, as shown in Fig. 3, without retarding the first matrix.

The advantage lies in the fact that a single escapement member will release the foremost matrix and arrest the second one with certainty. The invention in this regard consists, broadly, in the employment of a laterally inovable escapement with a matrix recessed for a portion of its length only. The escapements may be moved laterally by any suitable means, connected with finger keys or other actuating devices. In the drawings I have shown for the purpose a rock shaft E, mounted in the frame and provided at the rear end with a lip e, to act against the sides of the escapements; and at the front end with crank arms e' connected by links e'' to levers e^, which are in turn actuated by reeds e^ communicating with the keyboard.

It will be observed that the foremost matrices project at one corner beyond the magazines, and through the opening in the plate C, so that they must be returned or pushed backward into the magazines before the plate can be raised or lowered. I propose to utilize the escapements D, for this

purpose. To this end I mount them at the upper end on horizontal pivots d' , so that their lower ends may be swung rearward, as indicated in dotted lines, to push the matrices inward. For the purpose of thus moving the escapements I employ a horizontally movable bar d^2 , through which their lower ends extend, this bar being guided in the frame and operated by an angular hand lever F, the movement of which effects the backward movement of all the matrices; and the matrices thus returned to the magazine may be locked therein by the insertion of a transverse bar in a manner well understood; or by any other suitable means. When the locking bar is removed, the downward movement of the matrices serves to restore the escapements D to their normal or operative position. This feature in itself constitutes no part of my invention, as if desired this return movement of the bar d^2 might be effected by springs or connections to a hand lever (not shown).

Having described my invention, what I claim is:

1. The combination with a matrix having a body portion and ears projecting therefrom, of an escapement comprising a finger arranged to engage transversely with the said body portion between the ears and hold the matrix, and movable at right angles to the plane of the matrix to release it.

2. In a machine of the class described, an escapement consisting of a single finger formed on one side with a lip to engage the

matrices at their sides and transversely thereto and movable at right angles to the plane of the matrices to release them.

3. In a machine of the class described, matrices longitudinally recessed in their sides from their upper or rear end to a point near the forward end, in combination with a laterally movable escapement having a lip on one side to engage the forward end of the matrix, said lip adapted to enter the recess named after the matrix has advanced from its normal position, whereby the escapement is permitted to return to a position for engaging a second matrix while the first matrix is passing it.

4. In a machine of the class described, escapements having lateral lips in combination with the matrices having the longitudinal channel or depression b in their sides to receive the escapement lips and permit the passage of the matrices thereby.

5. In a machine of the class described, the combination of a magazine, the matrices therein, and the escapements movable in one path to control the discharge of the matrices and also movable in another path to restore protruding matrices to the magazine.

In testimony whereof I hereunto set my hand this 13th day of November, 1911, in the presence of two attesting witnesses.

ROBERT O. BOARDMAN.
